UNITED STATES PATENT OFFICE

169,419

TOY WALKING ELEPHANT

Laurie J. Campbell, Erie, Pa., assignor to Louis Marx & Company, Inc., New York, N. Y., a corporation of New York

Application December 30, 1952, Serial No. 22,931

Term of patent 7 years

(Cl. D34—2)

To all whom it may concern:

Be it known that I, Laurie J. Campbell, a citizen of the United States, and a resident of Erie, in the County of Erie, and State of Pennsylvania, have invented a new, original and ornamental Design for a Toy Walking Elephant, of which the following is a specification, reference being had to the accompanying drawing forming a part thereof, wherein:

Fig. 1 is a side elevational view of a toy walking elephant embodying my new design;

Fig. 2 is a rear elevational view of the same;

Fig. 3 is a bottom view of the same; and

Fig. 4 is a front elevational view of the same.

I claim:

The ornamental design for a toy walking elephant, substantially as shown.

LAURIE J. CAMPBELL.
